United States Patent Office.

LUTHER C. KEELER, OF MONTROSE, PENNSYLVANIA.

Letters Patent No. 65,815, dated June 18, 1867.

SHOE-HOLDER.

The Schedule referred to in these Letters Patent and making part of the same.

TO ALL WHOM IT MAY CONCERN:

Be it known that I, LUTHER C. KEELER, of Montrose, in the county of Susquehanna, and State of Pennsylvania, have invented a new and useful Device for Holding Sample Shoes; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

This invention relates to a new and improved device for holding sample shoes to boxes, and in conspicuous places in windows, show-cases, etc., and is designed to admit of the ready application of the shoe to the box or other place required, as well as its ready detachment or removal therefrom. In the accompanying sheet of drawings—

Figure 1 is a detached front or face view of my invention.

Figure 2, an end view of the same.

Figure 3, a section of the same taken in the line $\alpha\alpha$, fig. 1.

Figure 4, a front or face view of the same applied to a box and having a sample shoe fitted in it.

Similar letters of reference indicate like parts.

A represents a stirrup or plate, which may be constructed of sheet metal and bent in such a manner as to admit of the lower part of the shoe being fitted in it. (See more particularly figs. 2 and 4.) This stirrup or plate A has two sheet-metal supports B B attached to it, which diverge from each other from their lower to their upper ends, as shown clearly in fig. 1, and the upper ends of the supports are bent downward to form hooks $\alpha\alpha$, to fit or catch over the upper edge of a box, C, as shown clearly in fig. 2. On one of the supports B' there is fitted a clasp, D, which is simply a curved arm having a plate, b, secured to one end of it, to form a loop, which is fitted on the support B', and which may be shoved up and down thereon, and retained at any desired point by friction only. This clasp encircles the rear part of the shoe above the counter in the heel, and serves to support the shoe on the stirrup or plate A, as will be fully understood by referring to fig. 4.

By this simple device it will be seen that the shoe may be readily fitted to the box and detached therefrom, and the holder may be suspended in a window or show-case, and the shoe fitted in it with the greatest facility.

The clasp D may be adjusted higher or lower on the support B', to suit the size of the shoe. I would remark that one standard may be used instead of two, if desired, but I consider two preferable, as they would keep the holder more steady or firm in position, preventing it from swinging or oscillating when suspended in position. The holder may be constructed of sheet metal, wire, or other substances. The supports B B may be made any length, and the loops $\alpha\alpha$ inserted through holes made in the box, to support and keep the shoes in position.

Having thus described my invention, I claim as new, and desire to secure by Letters Patent, as a new article or manufacture—

A shoe-holder constructed as described, consisting of the standards B B', one or more, provided with hooks $\alpha\alpha$, stirrup or plate A, and clasp D, substantially as herein shown and described.

The above specification of my invention signed by me this 6th day of March, 1867.

LUTHER C. KEELER.
